UNITED STATES PATENT OFFICE.

WILLIAM A. WINTER, OF EAST ORANGE, NEW JERSEY, ASSIGNOR TO THE KNY-SCHEERER CORPORATION, A CORPORATION OF NEW YORK.

BANDAGE-WINDER.

1,287,163.

Specification of Letters Patent. Patented Dec. 10, 1918.

Application filed July 12, 1917. Serial No. 180,204.

To all whom it may concern:

Be it known that I, WILLIAM A. WINTER, a citizen of the United States, and a resident of East Orange, county of Essex and 5 State of New Jersey, have invented certain new and useful Improvements in Bandage-Winders, set forth in the following specification.

This invention relates to bandage winders. 10 The object of the invention is to provide a sturdy, durable machine for winding bandages, which will be efficient in operation, capable of cheap construction, and simple in operation. 15 In its preferred embodiment, the machine is motor driven and one object of the invention is to provide for the adaptation of a standard type of motor commonly known in the art as a sewing-machine motor.

20 A further object of the invention is to provide for the winding of bandages of various widths without the necessity of removing a head plate. Further objects of the invention are to improve in general the details of 25 construction of a machine of this character.

The above will be pointed out in the accompanying claims, which are directed to the accompanying drawings forming a part hereof, and the following specification as 30 merely illustrative and descriptive of one illustrative embodiment of the invention. Like characters represent corresponding parts in the several figures of the drawings, in which Figure 1 is a front elevation of 35 the machine mounted upon a table; Fig. 2 is a cross section with parts shown in elevation through the line II-II of Fig. 1; Fig. 3 is a detail vertical section, with parts broken away, showing the journal in the 40 bracket or frame; and Fig. 4 is a detail plan view of the motor-supporting platform.

A platform A of any suitable construction is provided, although the cross-shaped structure shown particularly well in Fig. 4 is preferred. This platform provides a plurality of pockets 1, one for the reception of each foot 2 of the motor B. The feet 2 form a part of a stationary base 3 of the motor, the body portion 4 of the motor being fixed to 50 the base 3 by a swivel 5, so that, through the medium of the spring 6, a clockwise tendency to rotate is imparted to the body 4, which carries the friction drive pulley 60 on its spindle. The platform A has suitably 55 fixed to it suitable clamps 7 and 8, which

serve to clamp the machine to a ledge such as the table C. An upright bracket D is mounted upon the ledge or platform A in a suitable manner, as by machine screws 9, taking into the tap holes 10 of the platform A. 60

A winding spindle E is suitably journaled in the bracket D, as through the medium of a journal box F. A friction drive wheel G is fixed to one end of the spindle E 65 and is adapted to coöperate with the friction drive pulley 6, which is upwardly spring-pressed against its lower edge. If desired, a manual means such as the handle H may also be provided to serve as means 70 for driving the winding spindle E.

A guide rod I is mounted in a horizontal position in the bracket D and extends out parallel with the winding spindle E.

A pair of head plates 11 and 12, symmetrical in structure, each has a bearing 13, provided with a set screw 14, and each likewise has a slot 15, extending to a mid-position from the periphery of the head plate, so that each head plate may be moved slidably 75 along the guide rod I to vary the space between the head plates 11 and 12 in order to accommodate various widths and various positionings of a bandage. Likewise, because of a slot 15, both head plates may be 80 swung so as laterally to clear the winding spindle E, or so as to be swung up laterally across the spindle E to form substantially spool ends for guiding the bandage to be wound. Although, so far as the guide rod 90 I is concerned, each head plate may have an independent swinging movement, it is preferred that some means be provided to cause the head plates to swing in unison when some fastening means such as the set screws 95 14 are released. In the embodiment illustrated, this means for causing the contemporaneous and uniform swinging of the head plates is comprised in the two guide fingers 16 and 17, which are fixed to the head plate 100 12 and which extend freely through snugly fitting sleeves 18 and 19, which sleeves are fixed to the head plate 11, and the removable finger 20 having threaded engagement at its threaded end 21 with the head plate 12 and 105 passing freely through the head 11. The knurled knob 22 may be useful in removing the spindle 20, if desired, to facilitate the threading of the winder.

A suitable detail construction for the 110

journal F is shown most clearly in Fig. 3. A journal box 30 is externally threaded for convenient mounting in the bracket D, the journal box being satisfactorily formed out of cast iron. A steel spindle 31 has a normal bearing fit with the bore 32 and extends outwardly to mount the drive wheel G, as through the medium of the key 33. The spindle 31 at the left has an enlarged portion, either formed integrally therewith or suitably fixed thereto and having cone bearings 34 and 35, the bearing 34 coöperating with the bearing face 36 and the bearing 35 coöperating with the bearing face 37. The bearing face 36 may be formed on a separate part such as the disk shaped member 38, adjustably mounted through the medium of the cap 39 having adjustable threaded engagement through the medium of the threads 40, with the journal part 30. A fixity of adjustment may be accomplished through the medium of the set screw 41, while a felt packing washer 42 may be interposed between the cap and the disk shaped member 38. A grease or oil cup 43 may take care of lubrication. A satisfactory method of threading the apparatus with a bandage to be wound is shown in the cross-section of Fig. 2, in which the bandage J preferably first passes over the guide rod I, then under the finger 17, over the spindle 20, and under the finger 16, thence to the winding spindle E. It is preferable that the slots 15 be arc-shaped relatively to the guide rod I as a center.

It should be noted that the part of the journal marked 44 is cylindrical and it is into this cylindrical part that the square shaped spindle is inserted and held fast by suitable means in a square shaped socket as by the pin 45.

What is claimed and what is desired to be secured by United States Letters Patent is:—

1. A bandage winder having a bracket; a winding spindle journaled in said bracket; means for rotating said spindle; a guide rod fixed to said bracket parallel to said spindle; a pair of head-plates each having a slot extending from its periphery to a mid-

position and rotatably and slidably mounted by said guide-rod whereby they may be rotated into and out of cooperation with said spindle and adjusted for various widths of bandage; and means for fixing said head-plates in position for operation as spaced abutments along said spindle.

2. In a bandage winder, a supporting frame; a winding spindle; a guide rod mounted on said frame; and a pair of swiveling head-plates, one or both of which are longitudinally slideable on said guide rod and which have slots to permit the lateral application of said head-plates to said spindle.

3. A bandage winder comprising a frame; a spindle journaled in said frame; driving means for said spindle; a head-plate for the journaled end of said spindle; a second axially adjustable head-plate having a swiveling mounting upon said frame and a spindle-clearing slot so that it may be swung in its own plane into and out of bandage confining position.

4. A bandage winder comprising a spindle; means for driving said spindle; a pair of spaced head-plates having slots to clear said spindle; a swiveling mounting for said head-plates to permit them to swing crosswise relatively to said spindle into and out of bandage confining position; and provisions to insure contemporaneous swinging in parallelism of both said head-plates.

5. A bandage winder comprising a spindle; means for driving said spindle; a pair of spaced head-plates having slots to clear said spindle, one or both of said head-plates being axially adjustable relatively to said spindle; a swiveling mounting for said head-plates to permit them to swing crosswise relatively to said spindle into and out of bandage confining position; and provisions to insure contemporaneous swinging in parallelism of both said head-plates.

In witness whereof I have signed my name to this specification this 9th day of July, 1917.

WM. A. WINTER.
